UNITED STATES PATENT OFFICE.

THEOPHILUS C. SCHIAFFNER, OF CHICAGO, ILLINOIS.

CHART FOR DRAFTING PATTERNS.

Application filed April 16, 1927. Serial No. 184,220.

My invention relates to a chart from which patterns may be drafted for the making of men's clothing, and the object of my invention is to provide a chart for each breast size 5 and from each chart a plurality of patterns may be made, and from each of said patterns men's clothing may be made which have the same breast size and varying waist size and other proportions properly arranged to fit 10 persons of the particular breast and waist measure.

Heretofore it has been a practice to make one waist size for each breast size and as a result the altering of clothing to fit persons 15 of different waist size from that made for a particular breast size, has been very great and the profits in the clothing business have been to that extent decreased, and by the use of my invention a large number of breast sizes 20 will be employed, and for each breast size a plurality of garments will be made having the other dimensions varied and properly proportioned as will be hereinafter explained. My invention will be best understood by reference to the accompanying drawings forming a part of this specification and in which,

Figure 1 is a top plan view of my chart on a reduced scale, having my invention incorporated therein.

Figure 2 is a view of a modified form of my invention which comprises a chart used more particularly for children's sizes.

In the drawings and for the purpose of illustration I have shown the preferred embodiment of my invention.

Referring to Fig. 1, line "B" represents the breast line, line "A" the top line, line "C" the waist line, line "D" the hip line and line "E" the bottom or length line.

This chart has been constructed to be used as a guide for making patterns for persons five feet ten inches tall and having a breast measure of forty inches, and the line "B" is shown extending from the center of the back 45 to the center of the front, that is, the chart is complete for one-half of the coat and the other half of the coat is obviously a duplicate of the half shown. The line 10 is the front line of the back portion of the coat and the 50 lines 11 and 12 are the back edges of the front portion of the coat representing the waist and breast size thirty-four inches and forty inches, respectively. Measuring from a point 13 where the continuation of line 10 crosses line 55 "B", to a point 14, is three-fourths of an inch and a line drawn from this point vertically

is tangent with the curve on the rear side of the armhole as indicated at 15. Measuring from 14 to a point 16 is one-fourth the breast measure or in this case is ten inches. A line 60 17 is drawn through this point perpendicular with the breast line and intersecting the top line or "A" line at the point 19, which will be hereinafter called the balance point upon which the proper fitting of a suit depends. The balance point 19 as shown in Fig. 1 is in the 65 proper position so that a coat with a forty inch breast and a thirty-four inch waist will exactly fit and properly balance when worn by a person possessing those measurements, and one important feature of my invention is to automatically adjust the balance point for the varying waist measurements and one given breast measure and this is accomplished by beginning at the point 18 and measuring toward the front of the coat one-eighth inch for 70 each inch increase in the waist measure. For instance, I have made this chart to show sizes from thirty-four to forty inch waist measure and from each point one-eighth inch apart 75 beginning at 18 may be drawn lines passing through the point 16 and intersecting the line "A". These lines will all lay between the points 18 and 20 on the waist line, they will all pass through and intersect at the pivot 80 point 16 and will intersect the top line between the points 19 and 21, and these points are designated by numbers 34 to 40, inclusive, and represent the position of the balance point as it is automatically shifted by this means for 85 the waist size 34 to 40, inclusive. Line 22 is of a suitable length to properly fit when the breast measure is forty and the waist measure is thirty-four inches, and line 22' represents 90 the same line in a shifted position corresponding with a forty inch breast measure and a forty inch waist measure. The angle which line 22 makes with line 23 is equal to the angle which line 22' makes with line 23'. In other words, the entire upper end of the chart 95 on the front side of the armhole and above the pivot point 16 shifts as a unit about said pivot point as the waist measure is increased, and the amount of this shifting is determined as heretofore explained.

On the waist line "C" are given a plurality of points 24 which represent the front edge of the required waist length and the distance from point 34 to the line 25 is the extra which must be allowed for the lapping of the coat, 100 similarly the distance between the point marked 40 and the line 26 is the overlap al-

- lowed on a coat having a forty inch waist measure. For each inch increase in waist measure the front edge of the coat is advanced one-fourth inch, the portion between the front 5 and rear halves of the coat is increased one-eighth inch as shown by the points 27, and the middle of the back is increased one-eighth inch on each half of the back material as indicated by points 28. The lines 29 and 30 10 are approximately of the same length and shape for the purpose of changing the front edges and upper corner of the coat automatically as this portion is rotated about the point 16 as previously described. At various places 15 about the outline of the chart are marked numbers 40 and 34, which in each case represent the boundary lines and points used for making patterns for coats of forty inch waist measure and thirty-four inch waist measure, 20 respectively, and the intervening distance between a forty and a thirty-four may be divided up as shown at various positions along the waist line, and lines may be drawn corresponding to these other points but they have 25 not been incorporated in the chart shown as a large number of lines is likely to cause confusion and for that reason I have shown simply the lines for the thirty-four and forty waist size for the one breast size and I have 30 shown the means by which the chart is automatically varied in order that a plurality of patterns of various waist measures and having the same breast measure may be designed by the use of this chart. The fore-going description has in the main part related specifically to one side of the coat but it is obvious that in order to make a complete coat two such sides must be used, which are of course duplicates. 35
- 40 In Fig. 2 I have shown another chart similar in principle to that shown in Fig. 1 but varying somewhat in that it relates to children's sizes, and this chart shows a top line "A", breast line "B" and a waist line "C".
- 45 As the breast measure is increased one inch the balance point 31 is automatically and progressively varied by means of lines drawn from points 32 through points 33, and the remainder of the coat is automatically varied 50 similar to that shown and described in Fig. 1.
- 55 While I have described my invention in its preferred form it is capable of variations without departing from the spirit of the invention, and I do not, therefore, wish to be limited to the precise details of constructions set forth but desire to avail myself of such variations and modifications as come within the scope of the appended claims.
- 60 I claim as my invention:
- 60 1. A chart for drafting a plurality of patterns of one breast size and each having different waist sizes; said chart comprising, a top line, a breast line and a waist line, each parallel with the others; a pivot point on 65 said breast line; a balance point on the top line vertically above said pivot point, corresponding to one waist size, and means for automatically varying said balance point for drafting patterns with the same breast size and having a plurality of waist sizes. 70
- 75 2. A chart for drafting a plurality of patterns of one breast size and each having different waist sizes; said chart comprising, a top line, a breast line and a waist line, each parallel with the others; a pivot point on said breast line; a balance point on the top line vertically above said pivot point, corresponding to one waist size; means for automatically varying said balance point for drafting patterns with the same breast size and having a plurality of waist sizes; lines drawn from said balance point and adapted to be adjusted automatically, together with said balance point, for indicating the outline of a portion of said patterns for said plurality of sizes. 80
- 85 3. A chart for drafting a plurality of the patterns of one breast size and each having different waist sizes; said chart comprising a top line, a breast line and a waist line, each parallel with the others; a curved line representing an armhole; a line perpendicular with and intersecting said breast line, and tangent to the rear side of said armhole line; a pivot point on said breast line at a distance of one-fourth the breast measure forward of said intersection; a balance point on the top line vertically above said pivot; a straight line from said balance point through said pivot point, to a point of intersection with the waist line; points measured in successive one-eighth inches forwardly of the last said point of intersection, from which lines are drawn through the pivot point and to the top line, for automatically adjusting said balance point, for each successive inch increase in 90 the waist measure. 95
- 95 4. A chart for drafting a plurality of patterns of one breast size and each having different waist sizes; said chart comprising, a top line, a breast line and a waist line, each parallel with the others; a pivot point on said breast line; a balance point on the top line vertically above said pivot point, corresponding to one waist size; means for automatically varying said balance point for drafting patterns with the same breast size and having a plurality of waist sizes; means for indicating the increase in the front and rear portions of said patterns, along said waist line as the waist measure is increased, and 100 means for indicating the outline of said patterns for said plurality of waist sizes. 105
- 110 5. A chart for drafting a plurality of patterns of one breast size and each having different waist sizes; said chart comprising, a top line, a breast line and a waist line, each parallel with the others; a pivot point on said waist line; a balance point on the top line vertically above said pivot point, corresponding to one waist size; means for auto- 115
- 120
- 125
- 130

matically varying said balance point for drafting patterns with the same breast size and having a plurality of waist sizes; means for indicating the increase in the front and rear portions of said patterns, along said waist line as the waist measure is increased,
5
10 the outline of a portion of said patterns for said plurality of sizes.

6. A chart for drafting a plurality of the patterns of one breast size and each having different waist sizes; said chart comprising a top line, a breast line and a waist line, each parallel with the others; a curved line representing an armhole; a line perpendicular with and intersecting said breast line, and tangent to the rear side of said armhole line;
15 a pivot point on said breast line at a distance of one-fourth the breast measure forward of said intersection; a balance point on the top line vertically above said pivot point; a straight line from said balance point through said pivot point, to a point of intersection with the waist line; points measured in successive one-eighth inches forwardly of the last said point of intersection, from which lines are drawn through the pivot point and to the top line, for automatically adjusting said balance point, for each successive inch increase in the waist measure; means for indicating the increase in the front and rear portions of said patterns for said plurality of sizes.

said patterns, along said waist line as the waist measure is increased.
35

7. A chart for drafting a plurality of the patterns of one breast size and each having different waist sizes; said chart comprising a top line, a breast line and a waist line, each parallel with the others; a curved line representing an armhole; a line perpendicular with and intersecting said breast line, and tangent to the rear side of said armhole line;
40 a pivot point on said breast line at a distance of one-fourth the breast measure forward of said intersection; a balance point on the top line vertically above said pivot point; a straight line from said balance point through said pivot point, to a point of intersection with the waist line; points measured in successive one-eighth inches forwardly of the last said point of intersection, from which lines are drawn through the pivot point and to the top line, for automatically adjusting said balance point, for each successive inch increase in the waist measure; means for indicating the increase in the front and rear portions of said patterns, along said waist line as the waist measure is increased; lines drawn from said balance point, adapted to be adjusted automatically, together with said balance point, for indicating the outline of said patterns for said plurality of sizes.
